UNITED STATES PATENT OFFICE.

OSCAR N. RITCHIE, OF HAMILTON, AND HERBERT C. BOYKIN, OF MIDDLETOWN, OHIO,
ASSIGNORS TO P. LORILLARD COMPANY, OF NEW YORK, N. Y., A CORPORATION OF
NEW JERSEY.

ARTICLE-FEEDING MACHINE.

Application filed May 9, 1921. Serial No. 467,985.

To all whom it may concern:

Be it known that we, OSCAR N. RITCHIE and HERBERT C. BOYKIN, both citizens of the United States, and residents of Hamilton and Middletown, respectively, in the county of Butler and State of Ohio, have invented certain new and useful Improvements in Article-Feeding Machines, of which the following is a specification.

10 Our invention relates to a machine for feeding articles such as bags, envelopes and the like and more particularly to a machine for feeding such articles from a source of supply to other apparatus for performing 15 further operations thereon; and has special reference to the provision of an article feeding machine of this type in which the articles are individually selected and automatically fed from the source of supply and delivered to such other apparatus.

In the present instance our invention comprehends the provision of a bag or envelope feeding machine adapted for effective cooperation with a bag opening machine of the 25 type disclosed in the patent to Henderson and Tietz, No. 1,111,899 of September 29, 1914, used for feeding, opening and filling envelopes or bags with a commodity such as tobacco. It will be understood, however, 30 that although we have shown our invention as adapted for and applied to such a bag opening machine, that our feeding machine is not limited to such use, our invention having a broader utility and being adapted for 35 feeding other articles where similar problems are involved. In the filling of tobacco in containers such as bags, a bag is selected from a source of supply and fed to apparatus which receives, grips and opens 40 the bag ready for filling, after which the bag is filled with the commodity and sealed. One of the difficulties in the apparatus used for performing these functions has been in the operation of the bag feeding machine. 45 In order for the associated opening, filling and sealing apparatus to operate efficiently, it is essential that the bags be fed to the bag opening apparatus singly and in timed 50 relation with respect thereto, it being further essential that the bags be fed each time without a "miss;" failure to deliver a bag to the opening machine at any one time or failure to deliver such bags singly or individually causing the associated apparatus 55 to be thrown out of operation, it being then

necessary to correct bag feeding activity prior to resumption of operation, this necessitating undue time consumption and preventing the greatest quantity production efficiency of the machine. The bag feeding machine hitherto used has been found to give unsatisfactory service, such machine at times failing to feed and deliver a bag and at other times feeding the bags in multiple instead of singly. Hand feeding has also been resorted to, this necessitating, however, a highly skilled operative for handling the machine with its concomitant disadvantages in materially increasing the cost of operation. Our invention therefore comprehends the provision of a bag feeding apparatus which will substantially unfailingly deliver the bags at properly timed intervals and which will deliver such bags singly or individually for proper cooperation with the associated bag opening apparatus.

Some of the difficulties in the bag feeding operations in the apparatus of the type here involved have had their source in the type of bag used. The bags used are not altogether uniform in thickness, the bags being of the type in which one side of the open end is a little longer than the other side of the said open end, with the closed end of the bag of somewhat greater effective thickness, with the result that the bags do not stack up in proper vertical alignment with each bag horizontally arranged, but stack up with one side wall of the stack higher than the other and with the top of the stack of smaller horizontal dimensions, as measured in the direction of bag length, than the bottom of such stack. Due to this inaccurate stacking of a pack of bags, a stack when placed in a magazine, the dimensions of which should be large enough to accommodate the full horizontal dimension of a bag in flat form, shows a tendency for the bags to creep and move out of alignment with respect to one another, presenting non-uniform conditions for bag feeding. Furthermore, the bags used are provided with a bottom edge which is not flat with the body of the bag but which is curled or bent in one direction, this being a characteristic imparted to the bag by the bag making operations. Such characteristic has been found to be troublesome in bag feeding, especially when the bags creep or move out of alignment in the magazine. The feeding of such

bags in feeding apparatus of the type previously used has been found to be attended with the disadvantages of multiple bag selection and the failure to feed the bags at each interval in properly timed relation. The provision of an apparatus in which the parts are so constructed and so correlated to overcome the prior disadvantages and to secure a machine in which individual bag selection and feeding is efficiently effected is a prime desideratum of our invention.

The principal objects of our invention therefore include, besides the provision of an apparatus having the characteristics and performing the functions above enumerated; the further provision of an apparatus in which the stacked containers or bags are properly guided in the magazine to minimize creeping or disalining of the bags; the further provision of apparatus in which the bags are alined in the magazine to present the bags to the feeding means in the desired condition; the provision of a magazine in which the containers or bags are supported to permit effective individual bag feeding activity; the provision of such a magazine co-operating with the feeding means to accomplish the desired end; the further provision of a feeding means in which the bags are curled to facilitate subsequent opening thereof and the general provision of an apparatus of this nature of simple construction and capable of accomplishing the desired functions with a minimum of operative parts.

To the accomplishment of the foregoing and such other objects as may hereinafter appear, our invention consists in the elements and their relation one to the other, as hereinafter particularly described and sought to be defined in the claims, reference being had to the accompanying drawings which show preferred embodiments of our invention and in which:

Figure 1 is a front elevational view of our feeding machine,

Figure 2 is an elevational view in cross section taken on the line 2—2 of Figure 1 showing our machine during one stage of its operation,

Figure 3 is a transverse view taken in cross section along the line 3—3, Figure 2, and

Figure 4 is a view in cross section with parts broken away showing the machine in a different stage of operation.

Referring to the drawings, the operative parts of the feeding machine are supported on a standard 10, which may comprise a casting, a main drive shaft 11 being supported in journals 12 in said casting, the said shaft 11 carrying a main drive gear 13 and a sprocket wheel 14, the sprocket wheel 14 receiving motion from any source of power (not shown) by means of the sprocket

chain 15. Supported on the standard 10 and fixedly connected thereto is a magazine, generally designated as 16, the said magazine comprising a plurality of vertical plates 17 connected together to form the side walls of a magazine shaft or well 18. The well 18 is adapted for the reception of a stack of articles to be fed and in the present instance is intended for the reception of a pack or stack of envelopes or bags 19, the said envelopes or bags being of the type in which one side of the open end thereof is longer than the other side of the said open end and in which the closed end of the bag is of greater effective thickness than the open end of the said bag, the bags for this reason stacking up in the shaft, as shown for example in Figure 2 of the drawings, the upper bags taking an angular position as shown, with one side wall of the stack higher than the other and with the longitudinal horizontal dimension of the stack being smaller at the top of the stack than at the bottom thereof.

It has been necessary to construct a magazine which will accommodate the articles to be fed, such as bags or envelopes, and to accommodate such articles in the flat so that the said articles should not be subjected to jamming or "sticking" when fed through the magazine shaft, the area of the shaft being made for this reason greater than the area of a bag or envelope. With such a construction and with the bags stacking up angularly, as hereinabove referred to, the bags show a tendency to creep and move out of relative alinement, the disalining of the bags having hitherto been one of the elements in preventing single bag selection and feeding at each required interval. Each bag or envelope, as hereinabove referred to, is provided at its bottom edge with a curled portion such as 20, shown particularly in Figure 4 of the drawings, the said curled portion being a characteristic imparted to the bag during the bag making operations. Such curled edge has been found to offer another disadvantage during the bag feeding operation, such curled edge having previously prevented proper alinement of the bags in the stack when placed in the magazine well, the disalining of the bags in connection with such curled edges having prevented the single or individual bag feeding as is essential. We therefore have found it desirable to provide means for minimizing "creeping" and disalining of the bags and to further provide means for realining the bags so that they are fed under uniform conditions for bag feeding. To this end we first provide the magazine 16 with walls 21 inclined to the opposed walls 22 of the magazine, the inclination of walls 21 being such as to conform to the inclined wall assumed by the stack of articles 19, as shown particularly in Figure 130

2 of the drawings. By these means the disalining of the bags or articles is effectively minimized. We have further found it desirable to provide means for realining the bags in the magazine, such means comprising pack or stack-adjusting elements operative on one edge of the stack, preferably the edge corresponding to the bottom of the bags 19, to align such bag edges in the magazine. Accordingly, we preferably provide adjusting means which in the present form of our invention take the form of a pack-adjusting cam 23, the said cam being mounted on a cam shaft 24 rotatable in opposed journals 25, mounted on the magazine plates 17, the shaft being provided with a gear wheel 26 receiving motion from the driving parts of the apparatus, as will further appear hereinafter, the cam 23 being arranged to move in the space between the front wall plates 17, the said cam being operative on the front edges of the bags 19, as shown in Figures 1 to 3 of the drawings. It has been found desirable to provide a plurality of such pack-adjusting cam elements and to arrange such cam elements in superposed relation. To this end we further provide a second cam 23' fixed to a second cam shaft 24', the shaft 24' being mounted in journals 25' preferably in the form of plates also connected to the front walls 17 of the magazine, the said shaft 24' carrying the gear wheel 26', which receives motion from the gear wheel 26 by means of an idler 27 journaled in bearings connected to the magazine 16. The pack-adjusting means or cams 23 and 23' are so contoured as to effect realinement of the bags 19, the cams being also operative to aid in the gravitational feeding of the said bags 19 in the magazine shaft, the cams being rotated clockwise, as viewed in Figure 2 and shown by the arrows in said Figure 2, this motion of the cams aiding in forcing the articles 19 downwardly in the shaft, as will be clearly apparent. It is desirable that these pack-adjusting elements operate intermittently on the stack for reasons that will appear further hereinafter and the provision of the elements in the form of cams rotatably mounted on the cam shafts is found desirable to attain this result.

The bags or envelopes 19 are selected one by one from the stack and are fed to other apparatus shown in the patent hereinabove referred to for opening and filling the bags with a material. Means is therefore provided for selecting and feeding the bags individually from the stack, the feeding preferably being from the bottom of the stack. To this end we provide a feed shoe 28 oscillatably mounted on a crank arm 29, the crank arm 29 being fixed on shaft 30 journaled in bearings in the standard 10. The shaft 30 being provided with gear wheels 31 and 32 at opposite ends thereof,

the gear wheel 31 meshing with the main drive gear 13 and receiving motion therefrom. The feed shoe 28 is preferably faced with a material such as rubber for the purpose of providing a frictional facing to frictionally select and feed a bag or envelope from the bottom of the stack. The feed shoe 28 is held yieldably on the crank arm 29 by means of the spring element 33 connected to both the shoe and the crank arm. 75 As will be apparent, on rotation of the main shaft 11, the feed shaft 30 will be rotated and the shoe 28 will at properly timed intervals frictionally contact with the bottom bag of the stack to feed the same forward. It has been found desirable to operate the friction feed in such manner that the shoe 28 engage and feed a bag after the cam adjusting elements 23 and 23' have been operative on the bags, the feeding 80 means and the pack adjusting means thus operating alternately on the bags, this correlation of parts being shown, for example, in Figure 2 of the drawings with the cams in dotted line position and preventing opposite components from being operative on the bags at the same time, this arrangement minimizing any tendency to jam or mar the articles or bags in the magazine. 85

For the purpose of minimizing multiple bag selection by the feeding means, we provide the restraining elements in the form of knives 34, the said knives being mounted on a knife block 35 detachably connected to the rear walls 22 of the magazine and 90 mounted on studs 36, the blocks being secured on the studs by means of nuts 37. The knives 34 cut into the bags 19, this being one of the elements in preventing the friction between the two bottom bags to 100 cause feeding of the bag next adjacent to the bottom bag of the stack. 105

We have found that the supporting means upon which the stack of bags 19 rest must so cooperate with the feeding means and 110 the pack adjusting means as to minimize multiple bag feeding and as to eliminate the possibility of the feeding means missing a bag during the operation thereof. To this end we have found it desirable to provide 115 the support 38 of the magazine with opposed track elements 39, the bags resting on the said track elements, it having been found desirable to provide such track elements with raised portions 40, the raised 120 portions 40 being provided adjacent the feed opening 41 of the magazine. The raised portions 40 are also cut away as at 42, the distance between the cut away portion 42 and the bottom end 43 of the front 125 plates of the magazine defining a predetermined feed opening to permit only a single bag with its curled front edge to be fed from the magazine. The tracks 39 provide therebetween a space or an opening through 130

which the feed shoe 28 is adapted to move for cooperation with the bags in the stack. The provision of the raised portions 40 and the predetermined feed opening 41, combined with the feeding means 28 and the cooperation between these parts, have been found to be essential in providing a construction to effect only single bag selection and feeding.

10 Means is provided for receiving the individual bags as fed forward by the feeding means, such means preferably comprising rotatable gripper rolls 44 arranged in spaced relation on shaft 45, the shaft 45 being provided with gear wheels 46, the gear wheels meshing with and receiving motion from pinions 47 mounted on a shaft carrying rolls 44' cooperating with rolls 44 from idlers 48 meshing with the feed gear wheel 31, the arrangement of the gears being such as to provide for the proper rotation of the gripper wheels 44 and 44' to feed the bags forward for further operation. Meshing with one of the gears 46 is an idler 49, the said idler meshing in turn with the gear 26 for imparting motion to the cam shafts and cam elements 23 and 23' hereinbefore described.

15 Before delivering the feed bags to the opening apparatus hereinbefore referred to it has been found desirable to effect a transverse curl or bend running longitudinally of each bag, this being desired to facilitate subsequent bag opening operation. The bags when delivered to the opening machine are received by a holder or a pan, means being provided such as a spoon adapted to be inserted between the sides of the bag at the open end thereof for the opening of the bag to place the same in condition ready for filling, such means being particularly disclosed in the patent to Henderson and Tietz hereinabove referred to. It has been found in practice that when the bag is fed to the supporting pan that if the longitudinal central portion of the bag does not lie flat against the pan support but is spaced therefrom, that the opening spoon when moved into cooperation with the pan and the bag, instead of feeding between the opposite sides of the bag to open the same, will move between the bag and pan support, thus failing to effect bag opening, this in turn causing a subsequent stopping 20 of the machine. It is desired, in order to facilitate the opening of the bags by the spoon, to produce or effect a transverse bend or curl in each bag as it is selectively fed from the magazine to the opening machine. By producing the transverse curl in the bag the longitudinal central portion thereof is ironed out and flattened with the side edges of the bag curled upwardly therefrom so that when the bag is received 25 by the pan it lies on the same with the

central part of the bag lying flat against the pan support and the opening spoon will invariably move between the side walls of the bag to effect the opening thereof. To this end we provide a roller 50 rotatably mounted in bearings 51, the roller being provided with a central recessed portion 52. Cooperating with the roller 50 and more particularly with the recessed portion 52 thereof is a drum 53 mounted on shaft 75 54, the shaft being provided with journal blocks 55 movably mounted in recesses 56, the said journal blocks 55 being resiliently mounted in said recesses to permit vertical motion of the drum 53, springs 57 and 80 housings 58 being provided for this purpose. The drum 53 has a width substantially equal to the width of the recessed portion 52 of the roller 50, the cooperation of these elements when receiving a bag from 85 the gripper rolls being operative on the bag to effect a transverse bend or curl therein running longitudinally of the bag, as will be clearly apparent by reference to Figure 4 of the drawings. Fixed to the shaft 90 of the roller 50 are opposed pinions 59 meshing with idlers 60, the idlers meshing in turn with pinions 47 and receiving motion therefrom. The drum shaft 54 is also preferably provided with pinions 61 meshing with the roller pinions 59. The cooperating roller 50 and drum 53 receive the bags as they are fed individually from the feeding means and the gripper rolls, and impart a curling effect thereto, as shown 100 in Figure 4 of the drawings, the bags after undergoing the curling operation falling on the guide or chute 62 and thence to the guiding means and bag holder or pan of the bag opening machine hereinbefore referred to.

105 The operation of our bag feeding machine will be in the main apparent from the above detailed description thereof. The bags 19 are inserted in pack or stack formation from the side or top of the magazine, the bags stacking up in the form shown in Figure 2, the bags being guided by the straight and inclined walls of the magazine to minimize the disaligning of the bags in the magazine. Any disalignement that takes place is corrected by the pack adjusting cams 23 and 23' operating on the front or bottom edges of the bags, these cams aiding and facilitating gravitational 115 bag feeding in the magazine shaft. Feed shoe 28 periodically engages the bottom bag of the stack and feeds the same forward through the magazine opening 41. The pack adjusting or cam means and the feed shoe preferably operate intermittently as described. The magazine support for the bags is contoured by the provision of a raised portion at the front part thereof to facilitate bag feeding and to eliminate, in 120 125 130

combination with the other elements, any possibility of multiple bag feeding, the elements being so correlated as to effect single bag feeding substantially without a "miss."

5 The bags as they are fed forward intermittently and successively by the feed shoes 28 are engaged by the gripper rolls 44 and 44', the bags being conducted or fed by these rollers to the cooperating roller 50 10 and drum 53 for producing a transverse curl or bend in each bag, after which the bags are moved gravitationally down the chute 62 to the bag opening machine (not shown) for opening and for subsequently 15 filling the bags with a commodity such as tobacco.

While we have shown our device in the preferred form, it will be obvious that many changes and modifications may be made in 20 the structure disclosed without departing from the spirit of the invention, defined in the following claims.

We claim:

1. In an article feeding machine, a stationary magazine adapted to hold a pack or stack of articles, means for feeding the articles forwardly individually from the stack and pack-adjusting means operative on the articles in the stack to condition the same for individual feeding, the said pack-adjusting means being arranged relatively to the magazine so as to be operative on the front edges of the articles therein and effective for moving or urging the articles rearwardly in the stack to cause alining of the opposite edges thereof.

2. In an article feeding machine, a magazine adapted to hold a pack or stack of articles, means for feeding the articles forwardly individually from the stack and pack-adjusting means operative on the articles in the stack to condition the same for individual feeding, the said pack-adjusting means being arranged relatively to the magazine and having a motion relative to the articles in the stack effective for moving the articles rearwardly to aline the opposite edges of the same and for moving the same downwardly to aid in the gravitational feeding 50 of the articles towards the said feeding means.

3. In an article feeding machine, a magazine adapted to hold a stack of articles, means for feeding the articles one at a time from the bottom of the stack and movable provisions operative on a predetermined number of articles in the stack at the front edges of the same and effective to move or urge the same transversely relatively to and over the articles below the same whereby the articles are separated and alined in the magazine.

4. In a machine for feeding articles such as bags, a stationary magazine adapted to hold a pack or stack of the articles, means

for selectively feeding the articles individually from the bottom of the stack, said feeding means being intermittently operative on the articles to feed the same successively in timed relation and pack-adjusting means intermittently operative on the stack at the front edges of the articles therein and effective to push the latter rearwardly in the stack to aline the front edges of the same in the magazine.

5. In a machine for feeding articles such as bags, a stationary magazine adapted to hold a pack or stack of articles, means for selectively feeding the articles individually from the bottom of the stack, said feeding means being intermittently operative on the articles to feed the latter successively in timed relation and pack-adjusting means intermittently operative on the stack at the front edges of the articles and effective to push a predetermined number of the articles rearwardly in the stack to aline the front edges of the same in the magazine, said article feeding means and pack-adjusting means being alternately operative on the magazine stack to secure individual bag selection and feeding.

6. In a machine for feeding articles such as bags, a magazine adapted to hold a pack or stack of the articles, means for selectively feeding the articles individually from the bottom of the stack and a plurality of superposed independent pack adjusting means operative on the stack at the front edges of the articles to aline the same in the magazine.

7. In a machine for feeding articles such as bags, a magazine adapted to hold a pack or stack of the articles, means for selectively feeding the articles individually from the bottom of the stack and pack adjusting cam means operative on the front edges of the articles for urging or pushing the articles rearwardly in the stack to aline the same in the magazine.

8. In a machine for feeding articles such as bags, a magazine adapted to hold a pack or stack of bags, frictional means intermittently operative for feeding the bags individually from the bottom of the stack and independent pack adjusting cam elements intermittently operative on the forward edges of the bags for alining the same in the stack and for aiding feeding thereof to the said feeding means, the feeding means and the elements being alternatively operative on the said stack.

9. In a machine for feeding articles such as bags, a magazine for holding a pack or stack of bags in which one wall of the stack assumes a position inclined to an opposed wall of the stack, the magazine being provided with an inclined guide means conforming to said inclined wall of the stack for guiding the same, means for selectively

- feeding the bags individually from the bottom of the stack and pack adjusting means operative on the stack to aline the bags in the magazine.
5. 10. In a machine for feeding articles such as bags, a magazine for holding a pack or stack of the articles in which one wall of the stack assumes a position inclined to an opposed wall of the stack, the magazine being provided with an inclined guide means conforming to said inclined wall of the stack for guiding the same and pack adjusting means associated with said magazine and operative on the pack to aline the articles therein in said magazine.
11. In a machine for feeding articles such as bags, a magazine for holding a pack or stack of the articles in which one wall of the stack assumes a position inclined to an opposed wall of the stack, the magazine being provided with an inclined guide means conforming to said inclined wall of the stack for guiding the same and a plurality of independent pack adjusting cam elements mounted in superposed relation on said magazine and operative on the pack to aline the bags in the magazine.
12. In an article feeding machine, a magazine adapted to hold a stack of articles, means for feeding the articles one at a time from the stack, means operative on the stack for alining the articles therein at one edge thereof and provisions for receiving the articles from the feeding means and operative on the articles for curling the same transversely.
13. In a machine for feeding articles such as bags, a magazine for holding a pack or stack of the articles, the magazine being provided with a straight wall and an inclined wall opposed thereto, the walls gradually contracting from bottom to top to accommodate a stack of the articles and means for selectively feeding the articles individually from the bottom of the stack.
14. In a machine for feeding articles such as bags, a magazine holding a pack or stack of bags, the magazine including a feed opening and a bottom support for the stack, means for feeding the bags individually from the bottom of the stack, each bottom bag being moved over the support and through the feed opening in the magazine during the feeding operation, the support being provided with a raised portion adjacent the feed opening of the magazine.
15. In a magazine for feeding articles such as bags, a magazine holding a pack or stack of bags, the magazine including a bottom support for the stack, the said bottom support comprising spaced apart track elements, each track element being provided with a raised portion at the forward part thereof and a feeding means for the bags movable in the space defined by the said track elements.
16. In a machine for feeding articles such as bags, a magazine holding a pack or stack of bags, the magazine including a feed opening and a bottom support for the stack, means for feeding the bags individually from the bottom of the stack, each bottom bag being moved over the support and through the feed opening in the magazine during the feeding operation, the support being provided with a raised portion adjacent the feed opening of the magazine and pack adjusting means operative on the pack to aline the bags in the magazine, said pack adjusting means cooperating with the bag feeding means and the support to secure individual bag selection and feeding.
17. In a magazine for feeding articles such as bags, a magazine holding a pack or stack of bags, the magazine including a bottom support for the stack, the said bottom support comprising spaced apart track elements, each track element being provided with a raised portion at the forward part thereof, a feeding means for the bags movable in the space defined by the said track elements and pack adjusting means operative on the pack to aline the bags in the magazine, said pack adjusting means cooperating with the bag feeding means and the support to secure individual bag selection and feeding.
18. In a machine for feeding articles such as bags, a stationary magazine adapted to hold a pack or stack of the articles, means for selectively feeding the articles individually from the bottom of the stack, means for restraining multiple bag selection, pack-adjusting means operative on the stack at the front edges of the articles therein and effective for moving or urging the articles rearwardly in the stack to cause alining of the front edges thereof and means for operating the pack-adjusting means.
19. In a machine for feeding articles such as bags, a magazine holding a pack or stack of bags, the magazine including a feed opening, and a bottom support for the stack, means for feeding the bags individually from the bottom of the stack, each bottom bag being moved over the support and through the feed opening in the magazine during the feeding operation, the support being provided with a raised portion adjacent the feed opening of the magazine and provisions for receiving the articles from the feeding means and operative on the articles for curling the same transversely.
20. In a machine for feeding articles such as bags, a magazine adapted to hold a pack or stack of bags, means for selectively feeding the bags individually from the bottom

- of the stack, pack adjusting means operative on the stack to aline the bags in the magazine, gripping means for receiving the bags from the feeding means and provisions receiving the bags from the gripping means and operative on the bags to effect a transverse curling therein.
21. In a bag feeding machine, provisions for advancing the bags from a source of supply, and feeding means receiving the bags from said provisions and operative for feeding the same to bag opening mechanism, the said feeding means including elements active on each bag for ironing or flattening the longitudinal central portion thereof and for creasing and bending the side edge portions of the bag upwardly therefrom, whereby subsequent opening of the bags by the bag opening mechanism is facilitated.
22. In a bag feeding machine, intermittently operative provisions for advancing the bags individually, and feeding means receiving the bags from said provisions and operative for feeding the same to bag opening mechanism, the said feeding means including superposed rollers active on each bag for ironing or flattening the longitudinal central portion thereof and for creasing and bending the side edge portions of the bag upwardly therefrom, whereby subsequent opening of the bags by the bag opening mechanism is facilitated.
23. In a machine for feeding bags, feeding means for feeding the bags from a source of supply to a bag opening mechanism, the said feeding means comprising provisions operative on the bags for ironing or flattening the longitudinal central portion of each bag and for creasing and bending the side edge portions of the bag upwardly therefrom whereby subsequent opening of the bags by the bag opening mechanism is facilitated.
24. In the method of feeding bags or envelopes to a bag opening mechanism, the step which consists in ironing out a longitudinal central portion of the bag and increasing and bending the side edge portions of the bag upwardly therefrom, whereby subsequent opening of the same by the bag opening mechanism is facilitated.

Signed at Middletown, in the county of Butler and State of Ohio, this 3rd day of May A. D. 1921.

OSCAR N. RITCHIE.
H. C. BOYKIN.
